Lewis A. Kimberly Inventor

United States Patent Office.

LEWIS A. KIMBERLY, OF NEW HAVEN, CONNECTICUT.

Letters Patent No. 96,443, dated November 2, 1869.

IMPROVEMENT IN STILTS.

The Schedule referred to in these Letters Patent and making part of the same.

To all whom it may concern:

Be it known that I, LEWIS A. KIMBERLY, of New Haven, in the county of New Haven, and State of Connecticut, have invented a new and useful Improvement in Stilts; and I do hereby declare that the following is a full and exact description of the same, reference being had to the accompanying drawings, and to the letters of reference marked thereon.

Figure 1 is a side view of my improved stilt.

Figure 2 is a rear view, showing the manner of fastening the step.

My invention relates to an improvement in stilts, and consists in making the step or foot-piece in such a manner that it may be easily adjusted to any height required.

The advantage of my invention is, that the step is made much lighter, more easily adjusted, and is cheaper than those hitherto used in this way.

To enable others skilled in the art to make and use my invention, I will proceed to describe the construction and operation of the same, with reference to the accompanying drawings.

A is the rod or staff of the stilt, to be made of hard wood, and may be either round or square, or in octagonal form.

B is the step, made of metal, and provided with two sockets or sleeves C D, as shown in figs. 1 and 2, which slide over or upon the staff, to which they are made to fit as closely as possible.

The outer portion of the upper socket C is centrally parted lengthwise of the staff.

Each portion is provided with an ear, *aa*, through both of which a set-screw, *b*, is passed, by which the two parts are drawn together, thus causing the socket to grasp the staff, and prevent the step from sliding therefrom, and firmly holding it in the proper position.

When this position is altered, the set-screw is loosened, and the spring of the metal loosens the socket, and the step can be forced either up or down the staff, as the case may require, and fastened in the manner above stated at any given point thereon, the entire length of the staff.

Having thus fully described my invention,

What I claim as new and useful, and desire to secure by Letters Patent, is—

As a new article of manufacture, the stilt, having an adjustable step, made in the form, and operated in the manner substantially as herein shown and described.

This specification signed and witnessed, this 11th day of September, 1869.

LEWIS A. KIMBERLY.
